DESIGN FOR A SIDING

John J. Cahill, Chicago, and Elmer F. McClintock, Oak Park, Ill., assignors to The Ruberoid Co., New York, N. Y., a corporation of New Jersey

Application March 26, 1935, Serial No. 56,062

Term of patent 7 years

To all whom it may concern:

Be it known that we, John J. Cahill, a citizen of the United States, residing at Chicago, in the county of Cook, State of Illinois, and Elmer F. McClintock, a citizen of the United States, residing at Oak Park, in the county of Cook, State of Illinois, have invented a new, original, and ornamental Design for a Siding, of which the following is a specification, reference being had to the accompanying drawing, forming part thereof, in which:—

Figure 1 is a plan view of one element of the siding shown in Fig. 2; and

Fig. 2 is a plan view of a siding showing our new design.

We claim:—

The ornamental design for a siding, substantially as shown.

JOHN J. CAHILL.

ELMER F. McCLINTOCK.
